UNITED STATES PATENT OFFICE.

ROBERT JOHN ROBINSON AND WILLIAM ANDERSON NELDEN, OF SALT LAKE CITY, UTAH.

WAVE-MOTOR.

SPECIFICATION forming part of Letters Patent No. 606,632, dated June 28, 1898.

Application filed September 3, 1897. Serial No. 650,513. (No model.)

To all whom it may concern:

Be it known that we, ROBERT JOHN ROBINSON and WILLIAM ANDERSON NELDEN, citizens of the United States, residing at Salt Lake City, in the county of Salt Lake, State of Utah, have invented certain new and useful Improvements in Wave-Motors, of which the following is a description, reference being had to the accompanying drawings and to the letters and figures of reference marked thereon.

Our invention relates to improvements in wave-motors.

Our object is to provide a construction in which the power-shafts are given positive rotation in a single direction and also to generally improve upon devices of this character.

To these ends the invention consists in the various matters hereinafter described and claimed.

In the accompanying drawings, Figure 1 is a top plan view, partly in section. Fig. 2 is a sectional side elevation, and Fig. 3 is a detail of the rack and pinion.

Generally speaking, the present motor includes a float located between the walls of a dock or similar structure, said float containing machinery for transmitting motion to a driving-shaft, double racks supported by the walls of the dock, and pinions upon suitable shafts carried by the float, said pinions meshing with the racks, whereby in the movement of the float upon the water and consequent movement of the pinions along the racks the shafts are rotated.

Referring now more particularly to the drawings, 1 1 represent the side walls of a dock or similar structure, and 2 represents the float, this float being hollow and open at its top, so that suitable machinery can be located within its walls. Between the side walls a a of the float are supported cross-beams a', and upon these cross-beams rest longitudinal beams a'', arranged in pairs, these beams being for the support of parts to be hereinafter mentioned.

Power-shafts c are journaled upon the sides of the float, one shaft being located near each end, and each of these shafts projects beyond one of the side walls. The projections are arranged upon opposite sides of the float and

are provided with pinions c', which mesh with the racks e upon the dock sides, this opposite arrangement being for the purpose of steady- 55 ing the float in its movement. Sprocket-wheels c'' are located upon the power-shaft c.

A suitable driving-shaft m, provided with the usual balance-wheel m' and driving-pulley m'', is centrally journaled upon the sides of the float, said driving-shaft having also the 60 sprocket-wheels m''' near its ends, while upon each set of beams a'' is journaled a counter-shaft n, carrying large and small sprocket-wheels n' n''. Suitable sprocket-chains o connect each sprocket c'' with the small sprocket 65 n'' upon the neighboring counter-shaft, and other chains o' connect the small sprockets upon the driving-shaft with the large sprockets upon the counter-shafts. Thus when motion is given the power-shafts it is transmitted 70 to the driving-shaft, and to the pulley upon the driving-shaft is connected the belt for transmitting the power as may be desired. In order to throw the machinery in the float into and out of operation, each sprocket-wheel 75 c'' and shaft c is provided with suitable clutch mechanism r. There is herein illustrated what is known in the trade as the "Reeves" clutch, and as its construction is well understood and forms no part of the present invention it will not be further described.

Passing now to the parts for giving rotation to the power-shaft c, a rack e is let into each side wall of the dock, each rack comprising a back plate e' and side flanges e'', these flanges being provided with inwardly-projecting teeth e''. Each rack is set diagonally in the wall, so that as the float rises the pinions will follow the racks and be rotated, the same result following as the float descends. The pinions engage the upper rows of teeth as the float ascends and the lower rows as the float descends, so that each pinion is constantly rotated in the same direction. Of course the distance between the 95 rows of teeth in each rack is greater than the diameter of the pinion, so that said pinion can freely rotate, and preferably the teeth of the racks approach the vertical, while the teeth of the pinions are correspondingly oblique to the radii, so that the pinions take firmly into the racks.

Manifestly the float can be placed between merely the side walls, or, if preferred, end walls can be built, thus inclosing the float, said end walls being provided with suitable inlet 5 and outlet gates 34, respectively. Of course power could be taken directly from one of the power-shafts *c*, and, if desired, only one power-shaft, counter-shaft, &c., need be employed. In the present structure, however, 10 the duplication of parts increases the power and also tends to balance and regulate the movement of the float.

Having thus described our invention, what we claim as new, and desire to secure by Letters Patent, is—

1. A wave-motor or the like comprising a stationary rack, a second stationary rack, a float adapted to reciprocate along the racks, a power-shaft upon said float, and a pinion 20 upon said shaft adapted to engage one of the racks in one movement of the float and to engage the other rack in the reverse movement of said float; substantially as described.

2. A wave-motor or the like comprising a frame, a power-shaft upon said frame, a pinion upon said shaft, and an obliquely-set rack 25 adapted to mesh with the pinion for rotating the shaft, one of the members, the rack or the frame, being vertically and horizontally 30 movable along the other; substantially as described.

3. A wave-motor or the like comprising a frame, a power-shaft upon said frame, a pinion upon said shaft, and an obliquely-set 35 double rack with which the pinion is adapted to mesh, one of the members, the rack or the frame having vertical and horizontal reciprocation along the other; substantially as described.

4. A wave-motor or the like comprising a frame, a power-shaft upon said frame, a pinion upon said shaft, and an obliquely-set 40 double rack having the teeth of one rack fac-

ing the teeth of the other, the pinion being adapted to engage the racks, and one of the 45 members, the frame or the rack, having vertical and horizontal reciprocation along the other; substantially as described.

5. A wave-motor or the like comprising an obliquely-set stationary double rack, a reciprocating float, a power-shaft upon said float, and a pinion upon said shaft adapted to engage one set of teeth in the rack in one movement of the float, and the other set of teeth in the reverse movement of the float; sub- 55 stantially as described.

6. A wave-motor or the like comprising a float, power-shafts upon said float, a driving-shaft upon the float between said power-shafts, cross-beams between the side walls of 60 said float, sets of longitudinal beams between the cross-beams, a counter-shaft journaled upon each set of longitudinal beams, connections between the power-shafts and the counter-shafts and between the counter- 65 shafts and the driving-shaft, stationary members at the sides of the float, and means between the stationary members and the power-shafts for rotating the latter in the reciprocation of the float; substantially as described. 70

7. In a mechanism of the character indicated, an obliquely-set rack, and a pinion adapted to mesh therewith, the teeth of said rack inclining in a direction opposite to the path of travel of the pinion, and the teeth of 75 the pinion being correspondingly oblique to the radii of the pinion; substantially as described.

In testimony whereof we affix our signatures in presence of two witnesses.

ROBERT JOHN ROBINSON.
WILLIAM ANDERSON NELDEN.
